CONTAINER CAP

Filed July 2, 1927

INVENTOR
Ralph A. Graham.
BY *Alfred Brown*.
ATTORNEY

UNITED STATES PATENT OFFICE

RALPH A. GRAHAM, OF KANSAS CITY, MISSOURI, ASSIGNOR, BY DIRECT AND MESNE ASSIGNMENTS, TO GRAHAM METAL MANUFACTURING COMPANY, OF KANSAS CITY, MISSOURI, A CORPORATION OF MISSOURI

CONTAINER CAP

Application filed July 2, 1927. Serial No. 203,171.

My invention relates to container caps and has for its object the regulating and control of flow through a spouted container cap.

In accomplishing this object I have provided improved details of structure, the preferred forms of which are illustrated in the accompanying drawings, wherein:

Fig. 1 is a perspective view of a container cap embodying my improvements installed on a container.

Fig. 2 is an enlarged sectional view of the neck of a container and of a container cap.

Fig. 3 is an enlarged plan view of the cap.

Fig. 4 is a dissociated view of the elements of the cap.

Referring in detail to the drawings:

1 designates a container and here for convenience illustrated as a bottle having a neck 2 to which is applied the cap 3 comprising the 20 annular body or skirt portion 4 and the integral horizontal flange element 5, a spout member 6 being illustrated as integral with the body member and rising from the flange member 5 thereof, the skirt depending from the outer edge or periphery of the flange. The spout member and the body communicate through an opening 7 and in ordinary practice the cap is screw-threaded on the neck of the bottle though a similar type of cap may 30 be provided for pressing on the neck of a bottle, the flange member 5 being ordinarily pressed against the upper edge of the neck.

The spout element 6 has a curved upper wall 8, and the horizontally directed spout outlet 9, the element being provided with an air vent 10 oppositely disposed to the outlet 9 and adjacent the juncture of the spout element with the flange for admission of air to the container to permit the outflow of fluid 40 from the container through the spout outlet.

I provide sealing means for stopping the flow and for sealing the opening whereby the flow may be controlled and comprising a valve element 11 and illustrated in detail in Fig. 4. The valve element comprises a cork gasket 12 or compressible sealing element of analogous nature having the central orifice 13, the gasket consisting of a disk positioned on the upper edge of the bottle neck and receiving the cap that may be screwed or

pressed upon the neck to seal the joint of cap with neck, the orifice 13 providing the outlet port for fluid from the container through the cap and spout.

The valve 11 consists of a disk 14 having the upturned annular flange 15 of slightly greater diameter than the orifice 13 for closing said orifice and a stem 16 being projected through the orifice and upwardly through an opening 17 in the spout member 6, whereby the valve 55 is positioned axially of the opening and its flange bears against the gasket adjacent the opening 7.

A coil spring 18 is sleeved on the stem exterior to the spout element and a head disk 19 is fixed to the end of the stem, the spring being compressed so that bearing against the head and the spout, it forces the valve into impressed and sealing engagement with the im- 60 pressible gasket 12.

The upper wall of the spout element is 70 instructed to provide the annular flange 20 around said opening 17 whereby a bearing and guiding collar or journal is provided for the reception of the valve stem 16 in alignment on the axis of the opening in the gasket.

The structure having been provided as described, the spouted cap in which the gasket and the valve element are assembled may be 75 installed on a container and the gasket properly impressed by secure engagement of the cap with the container to effect a seal. The spring 18, enforcing the valve against the gasket, prevents the outflow of fluid, either vapor or liquid, except under control of an operator, outflow being permitted by the depression of the head 19 against the spring 18 to space the valve from the disk orifice. The spacing may be of desired extent to permit the outflow of minute portions such as 80 drops of fluid in case of medicines or other carefully measured substances or for the steady, controlled flow which may be suspended by the release of the head for return of the valve to its seat by the spring 18.

While the invention has been illustrated as applied to a cap adapted to embrace the neck of a bottle, selected elements of the invention may be adapted for use in a cork closure or stopper. For example, the valve stem may be 100

installed in an aperture in a cork stopper, the spring 18 bearing against the upper surface of the stopper to impel the valve disk upwardly against the stopper to seal the aperture.

5. What I claim and desire to secure by Letters Patent is:

1. A device of the character described comprising in combination with a bottle, a cap including a skirt adapted to be applied to the neck of the bottle, an integral inwardly extending horizontal flange adapted to be pressed against the upper edge of the neck, and a spout integral with said flange and having a stem-receiving opening, a gasket interposed between the edge of the neck and the flange, a valve having an upturned edge flange and a stem extending through said spout opening and flange and having a head exterior to the spout, and a spring on said stem bearing oppositely against said head and the spout to urge the valve flange against the gasket.

2. In a device of the character described, a cap comprising a cylindrical skirt portion, a horizontal flange extending inwardly from the upper edge of the skirt portion and having a central opening, and a spout extending upwardly from the inner edge of the flange, the spout having a curved upper wall and a horizontally directed outlet, said wall being provided with a stem opening, a gasket having a central orifice seated in the cap and including a portion extending inwardly from the edge of the flange, a valve including a stem extending through the gasket orifice and said stem opening in the spout, a disk engageable with the gasket to close the gasket opening, and means for urging the valve against the gasket to press the gasket against the cap.

3. In a device of the character described, a cap comprising a cylindrical skirt portion, a horizontal flange extending inwardly from the upper edge of the skirt portion and having a central opening, and a spout extending upwardly from the inner edge of the flange, the spout having a curved upper wall and a horizontally directed outlet, said wall being provided with a stem opening and a vent port opposite said outlet, a gasket having a central orifice seated in the cap and including a portion extending inwardly from the edge of the flange, a valve including a stem extending through the gasket orifice and said stem opening in the spout, a disk engageable with the gasket to close the gasket opening, and means for urging the valve against the gasket to press the gasket against the cap.

4. In a device of the character described, an apertured cap having a skirt at its outer edge, a spout extending upwardly from the cap at the aperture thereof, said spout being curved to provide a laterally directed outlet and a curved upper wall, said wall having

an opening concentric with the aperture of the cap and being instruck around said opening to provide a stem guide, a gasket in the cap having a central opening, a valve including a stem extending through the gasket and the spout guide, a disk below the gasket and a head exterior to the spout, and a spring on said stem bearing against the head and the spout to urge the disk against the gasket for closing the opening therethrough.

5. In a device of the character described, an apertured cap having a skirt at its outer edge, a spout extending upwardly from the cap at the aperture thereof, said spout being curved to provide a laterally directed outlet and a curved upper wall, said wall having an opening concentric with the aperture of the cap and being instruck around said opening to provide a spring seat and a stem guide, a gasket in the cap having a central opening, a valve including a stem extending through the gasket and the spout guide, a disk below the gasket and a head exterior to the spout, and a spring on said stem bearing against the head and the seat of the spout to urge the disk against the gasket, for closing the opening therethrough.

In testimony whereof I affix my signature.

RALPH A. GRAHAM.
